US0D1085407S

(12) **United States Design Patent** (10) **Patent No.:** **US D1,085,407 S**
(45) **Date of Patent:** **** Jul. 22, 2025**

(54) **APPLICATOR FOR IMPLANTABLE DRUG DELIVERY**

- (71) Applicant: **Lupin Inc**, Baltimore, MD (US)
(72) Inventors: **Richard Holl**, Baltimore, MD (US); **Antonio Belton**, Chicago, IL (US)
(73) Assignee: **LUPIN INC.**, Baltimore, MD (US)
(**) Term: **15 Years**
(21) Appl. No.: **29/893,818**
(22) Filed: **Jun. 2, 2023**

(57) **CLAIM**

The ornamental design for an applicator for implantable drug delivery, as shown and described.

DESCRIPTION

FIG. 1 is a perspective view of an applicator for implantable drug delivery, showing our new design;

FIG. 2 is a left side view thereof;

FIG. 3 is a right side view thereof;

FIG. 4 is top view thereof;

FIG. 5 is bottom view thereof;

FIG. 6 is a front view thereof; and,

FIG. 7 is a rear view thereof.

The broken lines in the figures show portions of the applicator for implantable drug delivery that form no part of the claimed design.

1 Claim, 4 Drawing Sheets
